GORDON DON HARRIS, OF BAYONNE, NEW JERSEY.

EVAPORATING SYSTEM FOR MOISTURE-CONTAINING MATERIALS.

1,296,510.

Specification of Letters Patent.

Patented Mar. 4, 1919.

Continuation of application Serial No. 783,007, filed August 5, 1913. This application filed November 11, 1915, Serial No. 60,891. Renewed November 4, 1918. Serial No. 261,148.

To all whom it may concern:

Be it known that I, GORDON DON HARRIS, a citizen of the United States, residing at Bayonne, county of Hudson, and State of New Jersey, have invented a certain new and useful Evaporating System for Moisture-Containing Materials, of which the following is a specification.

This invention pertains to the art of drying moisture-containing substances of different kinds, such as peat which, as is well known, contains a high percentage of moisture, fertilizers of different kinds, such as humus and phosphates, paints and paint materials, such as white lead, soap, linoleums and other coated materials in sheet or web form, and many other kinds of materials.

In companion applications filed on even date herewith, Serial Numbers 60,889 and 60,890, there are disclosed an apparatus and a process for economically drying materials, the salient feature of which consists, among other things, in the operation of conditioning a drying medium, such as air, with a view to maintaining the drying medium at a predetermined temperature notwithstanding its repeated contacts with the masses of moisture-containing material, as a result of which conditioning operation the drying medium is maintained throughout its flow within all the chambers of the system at such a predetermined temperature that its capacity for absorbing moisture is not impaired to an appreciable extent by repeated contact with the masses of material. This is accomplished by reheating the drying medium, mainly, for the purpose of conditioning it so as to impart thereto a capacity for evaporating moisture from the material under treatment unimpaired substantially by the moisture absorbed during the flow of said drying medium through the several chambers, and while this substantially unvarying temperature of the drying medium is suitable for the treatment of certain substances, it is found unsuitable for the treatment of other substances containing a high percentage of moisture, or for treating substances which part with, or give off, their moisture slowly.

According to the present invention, the drying medium, is, preferably, heated to a predetermined temperature, and it is reheated alternately with its contacts with the material, so as to gradually or progressively

increase the temperature of the drying medium, with a view to expanding the volume of said medium and of imparting thereto a greatly increased capacity for evaporating moisture from the materials under treatment, whereby drying medium is so conditioned that, notwithstanding the reduction in temperature due to repeated contacts with the materials and the consequent absorption of moisture therefrom, said drying medium will be raised in temperature gradually by the reheating operations so that the outflowing current will have a temperature in excess of that of the initially heated inflowing drying medium. This renders the invention peculiarly suitable for the treatment of materials which contain a high percentage of moisture or which give off the moisture slowly, particularly in the operation of drying materials possessing such physical properties that said material are not injuriously affected by a high temperature moisture-absorbing agent.

Although I have mentioned air as the moisture evaporating agent to be circulated into contact with the materials, it is apparent that other agents, such as direct heat or boiler room gases, may be utilized in treating such materials as peat, or I may use steam or superheated steam for treating coated materials, such as linoleum, experience having shown that the oxidation of the coating applied to linoleums will be more rapidly effected by the use of an agent having a certain percentage of moisture and heated to a relatively high temperature.

As showing the vapor weight in grains which air is capable of absorbing to the point of saturation, per cubic foot, for various temperatures at ordinary atmospheric pressures, reference is made to the following table:

Degrees Fahrenheit.	Grains in a cubic foot.	
85	12.43	100
90	14.38	
95	16.60	
100	19.12	
105	22.	
110	25.5	105
115	30.	
130	42.5	
141	58.	
157	85.	
170	112.5	110

It is apparent that by reheating the drying medium so as to progressively increase or raise the temperature thereof as it flows through the several chambers and into contact with the successive masses of material, the capacity of said drying agent for evaporating moisture will remain unimpaired, notwithstanding the evaporation of moisture from the masses of material adjacent to the path of the flowing agent. Assuming the drying agent to be initially heated to 130° Fahrenheit, its volume is such as to carry 42.5 grains per cubic foot, and as it flows into contact with the successive layers, this capacity would ordinarily be decreased by absorption of moisture therefrom, particularly if the materials were of a nature to give off or part with moisture freely. This evaporation of moisture ordinarily decreases the temperature, but according to my invention the loss in heat units is compensated for by reheating the drying agent at frequent intervals so as to gradually raise the temperature, say to 141° Fahrenheit, at which temperature the drying agent has a capacity for carrying 58.0 grains per cubic foot, or in some cases said drying agent is reheated as it flows through the apparatus at 157° Fahrenheit, at which temperature it has a capacity for carrying 85.0 grains per cubic foot, as shown by the table.

The invention involves, also, the circulation of a gaseous drying agent back and forth so as to flow over and beneath the layers and into contact with the top and bottom surfaces of the material, and it includes, also, the circulation of a drying agent under pressure, say of one-half ounce to two or three ounces, so as to direct said agent against, and to secure an intimate contact of the drying medium with, the material under treatment.

The drawing illustrates diagrammatically one section of an evaporator embodying the present invention.

In the apparatus shown, A designates an exterior casing adapted to contain a series of trays E within a series of chambers so that the drying agent, usually preheated air, admitted to the casing will flow into contact successively with the material on the trays, and under pressure into contact with the top and bottom surfaces of the material on each tray, the interior of said casing being divided into a series of material-treating chambers and two series of heater-containing chambers, as will now be described.

In the upper part of casing A is a partition b which extends from one wall of the chamber nearly to the opposite wall thereof so as to produce an upper chamber B. The drying agent is admitted to this upper chamber by an inlet e, and within said upper chamber is positioned a heater C con-

sisting of coils of pipe through which is adapted to circulate a heating medium, such as steam or hot water. The drying agent is intended to be heated initially, prior to its admission by the inlet e, and the inflowing gaseous agent is heated by contact with the coils of heater C so as to raise its temperature to a substantial extent, when the drying agent when initially admitted is heated to a temperature suitable for contact with the material in the chambers.

Below the partition b and the upper chamber B formed thereby, is another partition d extending from one wall of the chamber nearly to the opposite wall thereof, similar to the partition b. The partitions b d produce between them a material-treating cell, chamber or compartment D, within which is supported a tray E, or its equivalent. Said tray consists usually of a suitable framework and an open wire mesh or foraminous bottom, thus constituting a perforated tray adapted for supporting the material within the chamber D. This foraminous tray occupies a horizontal position within chamber D, whereas the partitions b d are inclined slightly with respect to the horizontal tray, thereby providing tapering passages or spaces above and below the tray, respectively, through which passages or spaces the drying agent will flow in a manner to be slightly retarded by frictional contact with the partitions, as a result of which the drying agent is placed under pressure while in contact with the material. The tray E is positioned about midway between the partitions b d, and said tray is at some distance from the walls of casing A, thus resulting in chambers F G at the respective ends of chamber D. The chamber F is in communication with chamber B, so that the drying agent will flow from chamber B through chamber F, and into and through chamber D, said drying medium flowing over the material on tray E and being directed into contact with the upper surface of said material; thence the drying medium flows into and through chamber G, and is directed into contact with the under surface of the material resting on tray E, the drying medium thus flowing under pressure and into direct contact with both the upper and lower surfaces of the material on said tray.

Below the partition d are other partitions h i j k l m o extending from one wall of the casing nearly to the opposite wall thereof, and producing a series of material-treating chambers H I J K L M O adapted to contain a series of trays, each similar to the tray E in chamber D. The partitions thus described occupy an inclined relation to the trays within the chambers, so as to produce the tapering spaces above and below said trays, for the purpose of retarding

the flow of the drying agent, whereby the drying medium is placed under pressure, and is directed toward the top and bottom surfaces of the material so as to secure an intimate contact of said medium with such upper and lower surfaces of the layers of material present on the several trays.

Similarly, a series of chambers F' G' are provided at the respective ends of the chambers H to O, inclusive, said chambers F' G' being in communication with the material-treating chambers so that the drying agent will flow successively through the material-treating chambers and the heater-containing chambers. In the chambers F G F' G' are positioned suitable heaters or boosters P consisting of coils of pipes through which a heating medium is adapted to circulate; I may use steam, hot water, or any other medium for heating the drying agent which flows through the apparatus and successively into and through the material-treating chambers thereof.

An essential feature of the present invention consists in the employment of boosters or heaters having successively greater heating capacity; thus, the first booster or heater in the chamber F has a capacity for keeping the drying agent at the temperature to which it is raised by the action of heater C; the heater or booster in the chamber G has an increased capacity over the booster or heater in the chamber F, and so on throughout the series of boosters or heaters P in the successive chambers F' G' throughout the apparatus. As shown in the drawing, the successive boosters or heaters are constructed with increasing numbers of coils in order to secure the successively increased capacity required to progressively increase or successively raise the temperature of the drying agent flowing through the material-treating chambers.

The material or materials are placed on the trays and said trays are introduced into the material-treating chambers so that they will be intermediate the top and bottom partitions thereof. The drying agent admitted at inlet c is initially heated, say to a temperature of 80° Fahrenheit, and by flowing into contact with heater C the temperature of said drying agent is raised, say to 110° Fahrenheit. The drying agent then flows into contact with the upper surface of the material on the first tray, at which time the temperature of said agent is somewhat decreased owing to the evaporation of moisture from the material; thence the drying agent flows into contact with the first booster or heater, by the operation of which its temperature is increased to a desired degree; thence the drying agent flows into contact with the under surface of the material on the first tray. The drying agent then flows out of the first material-treating cham-

ber into the second booster chamber, and by contact with the second booster or reheater the temperature of the drying agent is again increased, so that it will flow into the second material-treating chamber at a raised temperature. The drying agent flows through the second material-treating chamber and into the third reheater chamber, back through the second material-treating chamber into contact with the booster or heater of the fourth reheater chamber, and this back and forth circulation is continued through the successive material-treating chambers and heater chambers. The drying agent is thus circulated into contact with the successive layers of material and is directed under pressure against the upper and lower surfaces of each layer, and into contact with boosters or reheaters in the intervals between its contacts with the material, as a result of which the drying agent is progressively increased in temperature by the boosters or reheaters so that the moisture-evaporating and moisture-carrying capacity of the drying agent is increased by the expansion in volume due to repeated reheatings. The drying agent is thus kept in a condition suitable for evaporating the moisture from a large number of layers of material, and from materials containing a high percentage of moisture, and owing to the action of the boosters or reheaters upon the drying agent it will flow out of the casing A through exit q at a temperature exceeding the temperature of the drying agent to which it is initially heated by the action of heater C.

The present application is a continuation of my prior application Serial No. 783,007 filed Aug. 5, 1913.

Having thus fully described the invention, what I claim as new, and desire to secure by Letters Patent is:—

1. In the art of drying moisture-containing materials, the process which consists in circulating a drying agent, heated to a predetermined temperature, into contact with successive masses of material and simultaneously therewith retarding the flow of such drying agent while in the presence of each mass so as to secure intimate contact with such material and during such circulation reheating or boosting the drying agent between the intervals of contact with the material and to increasingly higher temperatures for expanding the volume of such drying agent and increasing its absorptive power and the pressure under which such drying agent is brought into contact with successive masses.

2. In the art of drying moisture-containing materials, the process which consists in separating the material to be treated into individual masses within separate compartments, circulating a drying agent, heated

- to a predetermined temperature, through all the compartments and back and forth within each compartment and into contact with the upper and under surfaces of the mass of material therein and simultaneously therewith retarding the flow of said drying agent while in the presence of the mass and during the flow reheating the drying agent to increasing temperatures in excess of the initial predetermined temperature, and repeating the operations until the drying agent acquires a certain predetermined saturation of moisture.
3. In a drier, the combination of a series of material treating chambers, means for supporting the material in separated masses one within each chamber, means for circulating a drying agent back and forth within each chamber and into contact with the upper and under surfaces of each mass, the material-supporting means being so disposed with reference to the walls of the chambers as to oppose the free flow of the drying agent through said chambers and while in contact with the masses of material therein, and boosters or reheaters of successively increasing capacity positioned adjacent to the chambers and in the path of the drying agent flowing through said chambers.
4. In a drier, the combination of a series of chambers the walls of which form passageways, means for supporting material to be treated in separated masses one within each chamber, means for initially heating a gaseous drying agent to a predetermined temperature, boosters or reheaters positioned adjacent to the passageways and also positioned between the chambers, said boosters or reheaters being of progressively increasing capacity, and means for circulating the gaseous drying agent through the passageways, into contact with the masses of material in the chambers, and into contact with the boosters or reheaters in the intervals between its contacts with the successive masses and with the upper and under surfaces of each mass, the walls of said chambers and the material-supporting means being arranged with respect to each other so as to oppose the flow of the drying medium

and to secure an intimate contact of said drying medium with the upper and under surfaces of each mass.

5. In a drier, the combination with a series of material-treating chambers, and means for supporting the material in separated layers therein, of means for circulating a gaseous drying medium under pressure through the chambers successively and back and forth in each chamber and into contact with the top and bottom surfaces of each layer, and boosters or reheaters of successively increasing area and capacity for raising the temperature of the drying agent increasingly as it flows through chambers remote to the inlet, therefor, said reheaters or boosters being positioned in the path of the drying agent as it circulates back and forth in each chamber.

6. In the art of evaporating moisture-containing materials, the process which consists in separating the moist material into individual masses, circulating a gaseous drying medium, controlling the flow of said gaseous drying medium under pressure and into contact with each mass, and conditioning said drying medium during said circulation by reheating it in the intervals between its contacts with the masses and to progressively increasing temperatures between the initial and final periods of contact with said masses.

7. In the art of evaporating moisture-containing materials, the process which consists in separating the moist material into individual masses, heating a gaseous drying medium to a desired temperature and circulating said medium under pressure, controlling the flow of said medium by directing the same under pressure and in contact with each mass, said medium flowing into contact with said masses successively, and conditioning said drying medium during such circulation by reheating said medium to progressively increasing temperatures between its periods of initial and final contacts with said masses.

In testimony whereof, I have hereunto subscribed my name.

GORDON DON HARRIS.
